UNITED STATES PATENT OFFICE.

SIDNEY W. FARNSWORTH, OF PITTSBURGH, PENNSYLVANIA, ASSIGNOR TO WESTINGHOUSE ELECTRIC AND MANUFACTURING COMPANY, A CORPORATION OF PENNSYLVANIA.

VAPOR-RECTIFIER.

1,170,620.

Specification of Letters Patent.

Patented Feb. 8, 1916.

Application filed March 30, 1914. Serial No. 828,196.

To all whom it may concern:

Be it known that I, SIDNEY W. FARNSWORTH, a citizen of the United States, and a resident of Pittsburgh, in the county of 5 Allegheny and State of Pennsylvania, have invented a new and useful Improvement in Vapor-Rectifiers, of which the following is a specification.

My invention relates to containing receptacles adapted to maintain a high degree of 10 vacuum, and more particularly to containers of the type indicated and adapted to operate as vapor arc rectifiers.

One object of my invention is to provide 15 means for causing the wall of a containing receptacle to be absolutely impervious to the passage of gas or vapor.

Another object of my invention is to provide closing means for a containing receptacle which may be readily applied and removed and which, when applied, will make an absolutely gas-tight closure.

Prior to my invention, it has been a common practice to construct the containing receptacles of mercury arc-rectifiers of some suitable metal, such as steel. It has been found in practice that steel is apt to contain extremely minute pores through which small amounts of air or other gas may leak 25 into the evacuated interior of the containing receptacle. Furthermore, under certain conditions of high vacuum and high temperature, the steel itself appears to be sufficiently porous to admit minute quantities of 30 gas to the interior of the containing receptacle. I avoid the above noted disadvantages by coating one surface, preferably the outer one, of my containing receptacle with some fused vitreous enamel, which I 35 find effectively seals all pores in the metal and causes the wall of the containing receptacle to become absolutely gas-tight.

Referring to the accompanying drawing, Figure 1 is a view, partially in elevation and 45 partially in section, of one embodiment of my improved evacuated container, and Fig. 2 is an enlarged fragmentary sectional view of the joint shown at 5 in Fig. 1.

The body portion of an evacuated receptacle, such, for example, as the container of a vapor rectifier of the metal-case type is shown at 1 and closely adherent to the outer surface thereof is a vitreous or glazed enamel coating 2. The upper rim of the 50 bowl-shaped containing receptacle 1 is

ground to a flat surface, as shown at 3, and a cover member 4 is provided to so bear upon the surface 3 as to make an extremely close mechanical joint. A flange member 5 is welded to the wall of the member 1 a short 60 distance below the upper rim thereof. Seated on the cover member 4 and the flange member 5, respectively, are two peripheral rings 7 and 8, and, maintained in place by them, is a sealing pool of mercury 9 covering the flat joint between the member 1 and the member 4 and rendering it gas-tight. In order that the cover member 4 may be maintained firmly in place, a peripheral ring 10 is provided to bear firmly thereupon in close 65 proximity to the joint of member 1 and extending out over the sealing means, as shown at 11. Suitable threaded means 12 are provided for drawing the member 10 toward the flange member 5, thus providing a contact clamping means to hold the cover firmly 70 in place. Current is supplied to the rectifier by any suitable means, such, for example, as an anode lead 13, and is conducted from the cathode pool 14 through the wall of the container 11 and the flange 5 to a wire 15.

Having thus described my invention, what I claim is:

1. A container for vapor electric apparatus comprising a bowl-shaped receptacle 85 provided with a peripheral flange a short distance from the rim, a cover for the receptacle, clamping means engaging said flange and securing the cover in place, and retaining rings carried by the cover and the flange, respectively, and serving to maintain 90 a pool of sealing liquid over the joint between the receptacle and the cover.

2. A container for vapor electric apparatus comprising a bowl-shaped receptacle 95 provided with a peripheral flange a short distance from the rim, a cover for the receptacle, clamping means engaging said flange and securing the cover in place, and retaining rings carried by the cover and the flange, respectively, and serving to maintain 100 a sealing pool of liquid over the joint between the receptacle and the cover, said clamping means bridging over the sealing means.

3. A container for vapor electric apparatus comprising a bowl-shaped receptacle provided with a peripheral flange a short distance from the rim, a cover for the receptacle, sealing means for the joint between 110

the receptacle and the cover, a ring shaped member resting upon the outer surface of the cover and extending out over the sealing means, said means tending to draw said flange and said ring shaped member together.

4. A container for vapor electric apparatus comprising a bowl-shaped receptacle provided with a peripheral flange a short distance from the rim, a cover for the receptacle, sealing means for the joint between the receptacle and the cover, a ring shaped

member resting upon the outer surface of the cover and extending out over the sealing means, and threaded members engaging said flange and said ring member and tending to draw them together. 15

In testimony whereof, I have hereunto subscribed my name this 24th day of March 1914.

SIDNEY W. FARNSWORTH.
